Patented Jan. 9, 1923.

UNITED STATES PATENT OFFICE.

HARRY W. KOCH, OF CAMPBELLSPORT, WISCONSIN.

STEAM COOKING APPARATUS FOR CANNED FOOD.

Application filed November 10, 1920. Serial No. 423,077.

To all whom it may concern:

Be it known that I, HARRY W. KOCH, a citizen of the United States, residing at Campbellsport, in the county of Fond du Lac and State of Wisconsin, have invented certain new and useful Improvements in a Steam Cooking Apparatus for Canned Foods; and I do hereby declare the following to be a full, clear, and exact description 10 of the invention, such as will enable others skilled in the art to which it appertains to make and use the same.

This invention relates to a steam cooking apparatus for canned food, and the object 15 is to provide an apparatus which will receive the filled cans in somewhat large quantities, retaining them in spaced relation during the cooking operation, the cans being discharged automatically, or by gravity 20 from a series of retainers, or supporting devices upon the completion of the operation.

A further object is to provide a casing or retort fitted with steam inlet and outlet connections and means for rendering the 25 casing steam tight, together with a series of can retaining devices, or racks, so arranged that the cans will be distributed in a plurality of series within the casing, as they enter the latter, and upon the completion 30 of the operation, will be automatically discharged, the cans of the respective series feeding towards the discharge opening, by gravity.

A still further object is to provide in connection 35 with a casing mounted on an incline, a series of racks within the casing, the racks including guiding elements for the cans, whereby the latter are retained in regular order, and in a plurality of series 40 in parallel relation, the racks also being inclined, and the lower ends thereof being adjacent to the discharge opening, permitting the cans to pass out by gravity, the cans of the various series feeding toward a single 45 opening.

With the foregoing and other objects in view, the invention consists in the novel construction, combination, and arrangement of elements hereinafter described and 50 claimed.

In the accompanying drawings,

Figure 1 is a view of the casing or retort, in perspective, the steam-tight doors being closed,

55 Figure 2 is a view in vertical longitudinal section,

Figure 3 is a view in vertical transverse section, and

Figure 4 is a detail view illustrating a modified form of the racks or trays. 60

The main casing is designated 10, being preferably rectangular in cross section and open at each end. The casing is mounted in an inclined position, in order that the cans may be distributed within the casing, 65 in filling the device, by gravity, and also may be discharged by gravity at the close of the operation.

The open ends are closed respectively by doors 11 and 12, each mounted to swing on 70 hinges 13. The doors have steam-tight connection with the casing, suitable securing devices for this purpose being employed. In the drawings the doors are shown as being provided with a plurality of pairs 75 of ears 16, permitting the pins 17 pivotally mounted in lugs 18 on the frame, to swing into the space between the ears. The pins are threaded and are engaged by nuts 20 having operating wings 21. 80

A steam or water inlet connection is shown at 23 and a steam or water outlet connection at 24, while 25 indicates a steam gage, and 26 a temperature indicating device.

Within the casing or steam chest 10 I provide a series of inclined racks or trays 30, which may as shown in Figures 2 and 3 consist of angle bars 31 or which may as shown in Figure 4 consist of plates 31^a having dividers 31^b secured thereto, providing guide- 85 ways or tracks, for receiving the cans, guiding them as they pass into the steam chest, retaining them during the cooking operation and guiding the movement of the cans in the discharge operation. The angle elements are spaced apart according to the size of cans to be handled in a particular apparatus. A space 33 is provided at the entrance end, permitting of the distribution 90 of the cans to the various trays, and a space 34 is provided at the discharge end, the lower discharge opening being shown at 35. 95

While sizes and proportions are immaterial, so far as the present specification is concerned, it may be stated that the trays 105 will receive eight cans, placed approximately end to end across the steam chest or casing, and that ten trays or series of parallel tracks will be provided one above the other.

At the beginning of the operation, the 110 cans are rolled into the apparatus and are automatically distributed on the racks, the

doors are then closed and steam is applied for the required period, the lower door being then opened permitting the cans to roll out by gravity into boxing or labeling machines.

Changes, alterations or additions may be made within the scope of the appended claims.

Having thus described the invention what is claimed is:—

1. An apparatus of the class described having a plurality of runways one above the other, a supply runway of substantially the same width as said first mentioned runways, and all of said first mentioned runways communicating with said supply runway so that articles may travel by gravity through the supply runway to the first mentioned runways.

2. An apparatus of the class described having a plurality of runways one above the other, a supply runway disposed at an angle to said runways and of substantially the same width as said first mentioned runways, and all of said first mentioned runways communicating with the supply runway and being inclined relatively thereto so that articles may travel by gravity through the supply runway to the first mentioned runways.

3. An apparatus of the class described having a plurality of runways one above the other, a supply runway of substantially the same width as said first mentioned runways,

all of said first mentioned runways communicating with said supply runway so that articles may travel by gravity through the supply runway to the first mentioned runways, and a deflected portion at the junction of the lowermost of the first mentioned runways with the supply runway to facilitate the supply of material to the first mentioned runways.

4. An apparatus of the class described having tracks providing relatively close runways one above the other, a supply runway disposed at an angle to said tracks and of substantially the same width as said first mentioned runways, all of said first mentioned runways communicating with said supply runway and being inclined relatively thereto, the lowermost track extending into the supply runway and having a deflected portion therein, an outlet runway common to all of said first mentioned runways, and the lowermost track extending beyond the first mentioned runways and into the outlet runway at the base thereof whereby articles may travel by gravity through the supply runway to the first mentioned runways and from the latter by gravity through the outlet runway.

In testimony whereof I affix my signature in presence of two witnesses.

HARRY W. KOCH.
